UNITED STATES PATENT OFFICE

MENDUM R. BLUMENBERG, OF WASHINGTON, DISTRICT OF COLUMBIA.

DESIGN FOR A BUTTON.

SPECIFICATION forming part of Design No. 22,191, dated February 7, 1893.

Application filed January 4, 1893. Serial No. 457,288. Term of patent 3½ years.

To all whom it may concern:

Be it known that I, MENDUM R. BLUMENBERG, a citizen of the United States, residing at Washington, in the District of Columbia, 5 have invented and produced a new and original Design for Badge-Buttons, of which the following is a specification, reference being had to the accompanying drawings, in which—

Figure 1, represents a plan view of a badge button of my design, and Fig. 2, represents a side elevation thereof; both views being enlarged several times the contemplated size.

The new design which I have produced consists in the representation in relief of the head 5 of Christopher Columbus upon the upper surface of a metallic button composed of an upper disk slightly convex in section, the said head being a three-quarter full-face view fac-

ing the right, scant beard and mustache, with no hat or cap upon the head, the hair of which 20 is parted in the middle and hangs down to the shoulders. Above and below the said head is left a space for the insertion of suitable letters and figures, the said upper disk tapering slightly from the center to the edge, which edge 25 falls off abruptly in a concave bevel, thereby accenting the relief upon the surface of the button, the said button having a shank substantially as shown.

What I claim is:—

The design for a button as herein described and shown.

MENDUM R. BLUMENBERG.
